UNITED STATES PATENT OFFICE.

MICHAEL P. SCHMITT, OF NORTH CHICAGO, ILLINOIS.

GUIDE FOR GRINDING DEVICES.

Application filed November 8, 1921. Serial No. 512,449.

To all whom it may concern:

Be it known that I, MICHAEL P. SCHMITT, a citizen of the United States, and a resident of North Chicago, in the county of 5 Lake and State of Illinois, have invented a new and useful Improvement in Guides for Grinding Devices, of which the following is a full, clear, and exact description.

My invention relates to guides for grinding devices, and more particularly to that type of grinding device used for the sharpening of lawn mower blades and the like.

An object of my invention is to provide a guide for grinding device in which the 15 depth of the cut about to be made may be accurately determined.

A further object of my invention is to provide a guide for grinding device in which variation in the grinding of a straight blade 20 due to the elastic properties of the grinding wheel support is reduced to a minimum.

Other objects and advantages will appear in the following specification, and the novel features of the invention will be particularly 25 pointed out in the appended claim.

My invention is illustrated in the accompanying drawings, forming part of this application, in which—

Fig. 1 is a perspective view of an embodiment of my invention,

Fig. 2 is a sectional view along the line 2—2 of Fig. 1, and

Figure 3 is a partial sectional view of a part of the mechanism illustrated in Figure 1.

In carrying out my invention, I make use of the ordinary type of lawn mower grinding device, such as is illustrated in Fig. 1, the sub-base of which is shown broken away. 40 This grinding device consists in a central shaft 1 rotatably supported upon the frame 2. Means for connecting the shaft to a driving mechanism is provided in a pulley wheel 3 mounted at one end of the shaft. A grinding wheel 4 is rotatably supported upon a lever member 5 having for its fulcrum the shaft 1. The grinding wheel 4 is operatively connected by means of a chain 6 to a sprocket wheel 7. The sprocket wheel 7 is 45 feathered upon the shaft 1 so that it may be driven thereby and thus in turn drive the grinding wheel 4. The lever member 5 is free to travel, carrying with it the sprocket 7 upon the shaft 1.

50 Automatic means for feeding the lever 5 carrying the grinding wheel 4 from one end

of the shaft 1 to the other end is provided in a threaded feed shaft 8 which is placed in parallel relation with the shaft 1. Since the shaft 1 revolves at a considerable speed, 60 it is necessary to provide a reduction gear mechanism intermediate the shaft 1 and the feed shaft 8. In this case, the reduction mechanism comprises a large sprocket wheel 9 which is operatively connected by means 65 of a chain 10 to a relatively small sprocket wheel 11 carried by the shaft 1. The sprocket wheel 9 is operatively connected to drive the feed shaft 8. A supporting shaft 12 is disposed parallel and closely adjacent 70 the feed shaft 8 substantially as shown in Fig. 2.

A downwardly extending bracket member 13 is slidably disposed upon the supporting shaft 12. The bracket 13 is provided with a 75 rearward extending threaded sleeve portion 14, the threads of which are in mesh with the threads upon the feed shaft 8. The lever member 5 is movably engaged with the bracket 13 so that movement of the bracket 80 13 along the supporting bar 12 will carry the lever member 5 and the grinding wheel with it. The bracket 13 is also provided with adjustable means for limiting the downward movement of that portion of the lever 5 carrying the grinding wheel 4, the purpose of 85 which will hereinafter be described.

A finger member 15 is supported upon the lever 5 at the outer end thereof and carries an adjustable hook 16 which may be extended or drawn into the casing of the finger 15. The finger 15 may also be turned at various angles with respect to the lever 5 upon its fulcrum 17. A straight edge 18 consisting of a steel angle iron, one surface 90 19 of which has been ground to a true straight edge is movably supported upon a cross frame 20 of the frame 2 by means of 95 adjustable clamping members 21.

From the foregoing description of the 100 various parts of the device, the operation thereof may be readily understood. The practice in the past of grinding a straight blade of a lawn mower, as shown at 22, has been to rely upon the aforementioned adjustable means carried by the bracket 13 to limit the downward movement of the lever 5 carrying the grinding wheel 6. This adjustable means consists of a flanged clamp 105 23 which is secured by means of a bolt 24 in various positions along a slot 25 in the bracket 13. It will readily be seen that if a

blade 22 is secured in the machine and a grinding wheel 4 is operated and started in its travel along the blade 22 from one end of the supporting shaft 12 to the opposite end of the blade 22 that variation, when the grinding wheel approaches the middle point of the supporting shaft 12, is likely to occur on the edge of the blade as ground. This variation occurs in the shape of a slight hollow intermediate the length of the blade. The cause of this hollow is that the supporting shaft 12 and the feed shaft 8 both are apt to give slightly from the weight of the grinding wheel 4 as it approaches the central points of these shafts. Also, chattering of the grinding wheel 4 upon the blade 2 is likely to throw the lever 5 up slightly and in coming down it strikes the flanged clamp 23 in such a way as to cause a slight change in position of the clamp. Because of the leverage present in the relation of the weight of the grinding wheel 4 and the position of the bracket 13, almost any undue pressure or vibration of the wheel 4 will be likely to cause a strain on the shafts 8 and 12 to bring about a variation in the blade when ground.

This means of guiding the grinding wheel 4 relative to the blade 22 and its disadvantages are done away with in the present invention. The straight edge 18 is supported in substantially parallel relation with the blade 22. The hook 16 of the finger 15 is then adjusted so as to rest upon the surface 19 of the straight edge 18 in a manner to

limit the downward movement of the grinding wheel 4. If the hook 16 is now elevated until the grinding wheel 4 strikes the blade 22, the distance between the hook 16 and the surface 19 will be exactly the depth of the 40 cut to be made upon the blade.

It will be seen by employing the straight edge 18 there is absolutely no variation in the relation between the grinding wheel 18 and the blade from the beginning of the cut 45 until the finish.

This guide for grinding wheel may be applied to any of the grinding machines now in use without in any way effecting the operation of the means for grinding the 50 rotary blades of the lawn mower.

I claim:

The combination with a grinding machine having a power driven grinding wheel, a clamp for holding a straight blade transverse to said grinding wheel, and means for moving said grinding wheel from one end of said blade to the other, of a rigid angle bar having an accurately fashioned flat surface thereon, a pair of clamping members for adjustably securing said bar to said machine adjacent and parallel to said blade, and an adjustable finger associated with the support for said grinding wheel, said finger being adapted to rest on said flat surface to cause said grinding wheel to be limited in its engagement with said blade uniformly throughout the grinding operation. 60 65

MICHAEL P. SCHMITT.
